UNITED STATES PATENT OFFICE.

BUSHROD W. BELL, OF DALLAS, TEXAS.

WOOD PAVEMENT.

SPECIFICATION forming part of Letters Patent No. 281,233, dated July 17, 1883.

Application filed June 12, 1883. (No model.)

To all whom it may concern:

Be it known that I, BUSHROD W. BELL, a citizen of the United States of America, residing at Dallas, in the county of Dallas and 5 State of Texas, have invented certain new and useful Improvements in Wood Pavements, of which the following is a specification, reference being had therein to the accompanying drawings.

- 10 The object of this invention is to furnish an improved pavement which shall be strong, durable, and cheap, not being liable to decay nor become uneven, with perfectly water-tight concrete joints laid on a perfectly solid and 15 compact foundation of gravel, which can be easily cut through and readily reunited should it become necessary to cut through it to lay sewer or gas pipes or water-mains, or make connections with same.
- 20 The invention consists of an improved pavement formed of one or more courses of gravel of any degree of thickness, each layer to be well and compactly rolled with a heavy cylindrical roller, forming a perfectly solid road- 25 bed and irregular *bois d'arc* blocks, cut as nearly at right angles to their length as may be, generally in lengths of about eight inches, their diameters varying from about four to ten inches, placed on end upon this road-bed 30 of compacted gravel, and all pounded with a heavy pounder flat on the bottom, so as to bring all the blocks to an even and uniform surface, the spaces between the blocks to be 35 filled with screened gravel or sand, and well rammed in until perfectly solid, after which a hot composition of coal-tar and pitch (such as is used for roofing purposes) is poured into the interstices between the blocks, forming perfectly water-tight concrete joints.
- 40 Figure 1 represents a top view of a portion of my pavement. Fig. 2 is a vertical section of the same.

The road-bed is to be properly graded to a sub-grade of about twelve inches below the 45 established grade of the street, and to conform to the cross-section of the street. Before placing the ballast thereon the road-bed shall be well rolled with a cylindrical roller not less than five feet long, and to weigh not less than 50 five thousand pounds. A bed of bank sand

or gravel, or either of them, six inches deep or more, shall be placed upon the road-bed as prepared above, and shall be evenly spread and rounded to the shape of the street, and shall be well rolled with a cylindrical roller 55 not less than five feet long, and to weigh not less than five thousand pounds, so as to form a perfectly solid bed the entire width of the roadway; blocks to be stripped of bark, of cylindrical shape, and sawed at right angles 60 to the axis of the blocks out of good sound live *bois d'arc* timber, free from knots and other defects; shall be about six inches long, and from three to eight inches in diameter. Blocks must be placed on end, in a close compact manner, care being taken to so arrange the larger and smaller blocks together that the interstices between shall be left as small as possible, and no square holes formed, and make all spaces as near as possible of uniform 65 size; all blocks adjoining the curb to be split and the flat side placed against the curb, so as to make tight and even joints, each block to rest squarely upon its base without binding. Before spaces between the blocks are 70 filled with gravel the blocks shall be pounded with a pounder weighing not less than eighty pounds, twelve inches in diameter, and flat on the bottom, and the blocks are brought to an even and uniform surface. No teaming shall 75 be allowed over the pavement until the spaces are filled with gravel; the spaces between the blocks to be filled with screened gravel or sand, and rammed in until solid with iron or steel bars, then covered and refilled, and swept 80 off with a coarse broom. A hot composition of coal-tar and pitch, (such as is used for roofing purposes,) and not less than one and one-fourth gallon per square yard, shall be poured 85 into and over the spaces. Then the whole surface shall be covered with gravel and sand to a depth of three-fourths of an inch. Cross-walks shall be made at all intersecting streets ten feet wide, level with the center-line of the street, and the ends to be on a level with the 90 curb, and to be crowned two inches higher than the paving.

I am aware that two layers of boards have been used for a foundation, as also a foundation of broken stone and gravel or either of them, 100

and that irregular blocks are old for paving purposes; but

What I claim, and desire to secured by Letters Patent, is—

5 A wooden pavement consisting of irregular *bois d'arc* blocks resting on a foundation of gravel, and having their interstices filled with a water-tight concrete of gravel, coal-tar, and pitch, as herein shown and described.

In testimony whereof I affix my signature in the presence of two witnesses.

BUSHROD W. BELL.
